TOP ROLL ASSEMBLY FOR FIBER ATTENUATING APPARATUS

Burrel C. Cole, 1328 13th St., Columbus, Ga., assignor of fifty percent to Charlton H. Williams, Columbus, Ga.

Filed June 4, 1962, Ser. No. 199,910

11 Claims. (Cl. 19—253)

This invention relates to a top roll assembly for fiber attenuating apparatus and more particularly to an over arm assembly for positioning and weighing top roll units.

An object of my invention is to provide a top roll assembly for fiber attenuating apparatus which may be pre-assembled and installed in an over arm by means of a single bolt, slotted opening and an exposed nut and at the same time permitting forward or rearward adjustment of the complete assembly to establish correct position without changing predetermined pressure distribution.

Another object of my invention is to provide a top roll assembly of the character designated which shall include improved leverage mechanism for applying pressure whereby a relatively light and sensitive single coil spring, or the like, may be employed.

Another object of my invention is to provide a top roll assembly of the character designated which shall be particularly adapted for dual apron type apparatus having self-tightening bottom aprons.

Another object of my invention is to provide a top roll assembly of the character designated which shall include exposed means for adjusting the lever of the pressure lever, thereby permitting accurate adjustment without disassembly.

Another object is to provide a spring loaded pressure unit wherein exact compression may be obtained by an arm level adjustment and visible means is provided for determining when correct compression is obtained.

A further object of my invention is to provide a top roll unit of the character designated which shall be simple of construction and one which permits predetermined adjustments to properly distribute pressure on all top rolls and at the same time may position and align certain of the top rolls.

A further object of my invention is to provide a top roll assembly wherein pressure is applied on the neck of a top roll forward or rearward of a plane passing through the centers of superimposed bottom and top rolls, thus reducing or increasing normal forward thrust on the top roll.

A still further object of my invention is to provide a top roll assembly of the character designated in which pressure is applied to a connector bracket extending between a pair of top rolls by a roller element which engages an elongated groove or recess in the top of the connector bracket, the base of the groove being at an angle to a plane passing through the centers of superimposed top and bottom rolls to thereby decrease or increase normal forward thrust.

Heretofore in the art to which my invention relates, it is well known that a pair of bottom line aprons encircling a bottom line roll and bottom nose bar or bars may be employed to position and align top and bottom nose bars and one or more top rolls, thus automatically tightening the bottom aprons. Where only one top roll is involved in the unit, the normal forward thrust is approximately that required for tightening the bottom apron. However, when two or more top rolls are employed in the unit, the normal forward thrust is too great and the bottom aprons pass around the nose bars with excess friction. This not only interferes with smooth travel of the aprons, but also increases the torque load on the bottom line roll, thus overloading the gearing employed in driving the apparatus. To overcome these objections, I provide a top roll

2

assembly wherein pressure is applied at an angle to a connector bracket which connects a pair of top rolls, thereby decreasing the normal forward thrust. However, if desired, the forward thrust may be increased by changing the angle at which pressure is applied to the connector bracket for the top rolls.

Top roll assemblies embodying features of my invention are illustrated in the accompanying drawings, forming a part of this application, in which:

10 FIG. 1 is a vertical sectional view through a complete assembly;

FIG. 2 is a fragmental sectional view taken generally along the line 2—2 of FIG. 1;

15 FIG. 3 is a top plan view, drawn to a smaller scale;

FIG. 4 is an exploded view showing the pressure applying levers, the connector bracket for a pair of rolls and the nose bar assemblies therefor;

20 FIG. 5 is a vertical sectional view through a modified form of my invention in which a four roll drafting assembly is employed; and,

FIG. 6 is an enlarged isometric view showing the top nose bar for the assembly shown in FIG. 5.

25 Referring now to the drawings for a better understanding of my invention, I show a roll stand 10 supporting front, middle and back line rolls 11, 12 and 13, respectively.

30 Mounted for rotation above the middle bottom line roll 12 is a middle top roll 14. Mounted for rotation above the back bottom line roll 13 is a back top roll 16. The top rolls 14 and 16 are held in spaced relation to each other and in parallel alignment with the bottom line rolls 12 and 13 by a connector bracket indicated generally at 17. The connector bracket 17 is provided with transverse recesses 18 and 19 for receiving the shafts of the top rolls 14 and 16, respectively. Suitable spring grip members 21 extend between the recesses 18 and 19, as shown in FIG. 1 in position for the free ends thereof to engage the shafts of the rolls 14 and 16 whereby the rolls are held within the recesses 18 and 19. The spring clip member 21 is secured to the connector bracket 17 by a suitable screw 22. The spring clip member 21 thus permits the rolls 14 and 16 to be snapped into and out of the recesses 18 and 19.

35 Forwardly opening slots 23 and 24 are provided in the 45 forward end of the connector bracket 17 for receiving top and bottom nose bars 26 and 27, respectively. The nose bars 26 and 27 are held within the slots 23 and 24 by suitable means, such as a metal clip 28 having a curved upper end for easy handling. A suitable opening 29 is provided through the clip member for receiving a retaining screw 31. As shown in FIG. 1, the uppermost slot 23 has a greater depth than the lowermost slot 24 where a shim 32 may be inserted at either side of the top nose bar 26 to thereby vary the distance between the nose bars 26 and 27.

40 50 Pressure is applied to the connector bracket 17 by an over arm assembly indicated generally at 33. The over arm assembly comprises a generally U-shaped housing 34 which is pivotally supported by a pivot pin 36 from a base member 37 which in turn is attached to a torsion bar 38 carried by the roll stand 10. The housing 34 is raised and lowered by a toggle lever 39 having pivot pins 41 and 42 and an upstanding, internally threaded sleeve member 43. Threadedly engaging the sleeve 43 is a threaded member 44 having a suitable recess 45 therein for receiving an operating tool whereby the threaded member 44 may be rotated to vary the effective length of the toggle unit 39. Threadedly engaging the member 44 at the base of the U-shaped housing 34 are lock nuts 46 and 47.

45 55 60 65 70 75 80 85 90 95 99 Mounted for sliding adjustment relative to the under surface of the base of the U-shaped housing 34 is a

mounting bracket 48 having depending members 49 adjacent the forward end thereof. The mounting bracket 48 is adjustably connected to the housing of the over arm by a suitable bolt 51 which passes through an elongated slot 52 provided in the housing of the over arm. The bolt 51 is secured in selected positions by a nut 53.

Pivots connected to the depending members 49 is a first pressure lever arm 54, there being suitable openings 56 in the depending members 49 and suitable openings 57 in the lever arm 54 for receiving a pivot pin 58. Interposed between the other end of the pressure lever member 54 and the inner surface of the mounting bracket 48 is a compression spring 59. A suitable opening and spring guide 61 is provided to restrain movement of the lower end of the spring 59 relative to the lever 54. Also, the mounting bracket 48 is provided with a suitable depression 62 for holding the upper end of the spring 59 against shifting relative to the mounting bracket.

Pivots connected to the pressure lever 54 intermediate the pivot pin 58 and the spring 59 is a yoke 63. Suitable openings 64 are provided in the yoke 63 for receiving a pivot pin 66. Adjustably connected to the yoke 63 is a second pressure lever 67. An elongated recess 68 is provided in the pressure lever 67 for receiving a depending member 69 carried by the yoke 63 whereby the yoke is adapted for adjustment relative to the pressure lever 67. The bottom of the recess 68 is defined by a transverse member 71 having an elongated slot 72 therein for receiving a screw 73 whereby the depending portion 69 of the yoke 63 is connected to the pressure lever 67 at selected positions.

The width of the pressure lever 67 is substantially equal the width of the inside of the U-shaped housing 34 whereby the pressure lever 67 is held in parallel alignment with the U-shaped housing 34 of the over arm. A transverse recess 74 is provided in the forward portion of the pressure lever 67 for receiving the shaft 76 of a front top roll 77. A spring clip 78 is secured to the pressure lever 67 in position to engage the shaft 76 whereby the front top roll 77 is held within the recess 74.

The rear end of the pressure lever 67 is bifurcated to provide rearwardly extending legs 79 and 81. Mounted for rotation between the legs 79 and 81 is a disc-like roller 82 which is supported by a pin 83 which extends through the roller 82 and suitable openings 84 provided in the legs 79 and 81. The upper surface of the connector bracket 17 is provided with an elongated groove 86 which is of a width substantially the width of the roller 82 whereby the roller 82 is adapted for free rotation within the groove 86. As shown in FIG. 1, the groove 86 is inclined in a forward direction whereby force is exerted in a direction to reduce normal forward thrust on the top rolls 14 and 16.

The pressure lever 54 is offset as at 87 to provide a rearwardly extending portion 88 which engages the spring 59 and extends past a vertically extending opening 89 which permits the operator to view the position of the pressure lever 54 and thereby determine when proper spring compression is provided. To adjust spring compression, the nut 46 is loosened and the adjusting, threaded member 44 is rotated in the proper direction to move the pressure lever 54 to the proper level. The compression springs 59 has a given capacity when compressed to a given length and the pressure applied to the pressure lever 67 is calculated according to the leverage of pressure lever 54 in a manner well understood in the art. Although the compression spring 59 is concealed, the vertically extending slot 89 permits proper adjustment.

Passing around the middle top roll 14 and the top nose bar 26 is a top apron 91. In like manner, a bottom apron 92 passes around the middle bottom roll 12 and the lower nose bar 27. To prevent lateral shifting of the aprons 91 and 92 relative to the nose bars 26 and 27, I provide outwardly projecting guide pins 93 which are disposed at the sides of the aprons.

To install the top roll unit, the forward end of the over arm is lifted whereby it pivots about the pivot pin 36. The top aprons 91 are preinstalled around the top nose bar 26 and the middle top roll 14 whereby they are held in lateral position by the guide pins 93. The bottom aprons 92 are installed by lifting the back top roll 16 which causes the lower nose bar 27 to move inwardly toward the middle bottom roll 12. In this position, the apron will pass freely over the guide pins 93 for installation about the middle bottom roll 12 and the lower nose bar 27. Upon lowering the back top roll 16, the lower nose bar 27 moves away from the bottom middle roll 12 whereby the bottom apron 92 will not pass over the guide pins 93. To remove the top roll unit, a reverse procedure is followed.

With the aprons in place, the over arm is lowered whereby the front top roll 77 contacts the front bottom roll 11 and the disc roller 82 contacts the base of the elongated groove 86 in the connector bracket 17. A plurality of openings 84 are provided in the legs 79 and 81 whereby the roller 82 may be moved to selected positions along the groove 86. With the apparatus thus assembled, pressure is applied to all three top rolls 77, 14, and 16 according to predetermined calculations. Forward position of the front top roll 77 may be adjusted to proper location by loosening nut 53 on bolt 51 which permits relative movement between the mounting bracket 48 and the base of the U-shaped housing 34, thereby relocating the complete pressure unit. To prevent the compression spring 59 from reaching its maximum expansion when the over arm is lifted, extension 88 of lever 54 strikes the upper surface of base member 37.

In operation, the normal travel of the bottom aprons 92 causes the top aprons 91 to follow. With the aprons thus rotating, the top roll unit consisting of the nose bars 26 and 27, connector bracket 17 and the top rolls associated therewith has a tendency to thrust forward. Since the middle line top roll 14 and the back line top rolls 16 are normally forward of the center line of the subjacent, cooperating bottom line rolls when vertical pressure is applied, this forward thrust is greatly increased and is restrained only by the pair of bottom aprons 92. To prevent the bottom aprons from becoming too tight for free travel around the nose bars, the forwardly inclined base of the recess or groove 86 is engaged by the roller 82 whereby a portion of the downward pressure is rearwardly. That is, the application of the pressure in a downwardly and rearward direction offsets a portion of the forward thrust. Accordingly, by precalculation, any desired tension of the bottom aprons may be established and at the same time the top roll assembly is perfectly free to adjust its position according to the diameters of the bottom aprons 92.

Referring now to FIGS. 5 and 6 of the drawing, I show a slightly modified form of over arm assembly which may be employed on four line, double draft systems. The assembly indicated generally at 33^a comprises a generally U-shaped over arm housing 34^a having a mounting bracket 48^a adjustably connected thereto by a bolt 51^a and nut 53^a. The mounting bracket 48^a has depending members 49^a which are pivotally connected to the forward end of a pressure lever 54^a by a pivot pin 58^a. The rear end of the pressure lever 54^a indicated at 88^a extends past a vertical slot 89^a.

A compression spring 59^a is interposed between the mounting bracket 48^a and the rear portion of the pressure lever 54^a whereby downward pressure is exerted on the rear end of the pressure lever 54^a, in the same manner as pressure is applied to the rear portion of pressure lever 54 described hereinabove. A second pressure lever 67^a is pivotally connected to the pressure lever 54^a intermediate the pin 58^a and the spring 59^a by a pivot pin 66^a. The pressure lever 67^a is connected to the pin 66^a by a yoke member 63^a having a depending portion 69^a which rides in an elongated recess 71^a provided in the

pressure lever 67^a. The member 69^a is held in selected positions by suitable means, such as a screw or bolt 73^a.

Connector brackets 17^a are adjustably connected to each end of the pressure lever 67^a by pivot pins 96 and bracket members 97. The bracket members 97 are adjustably connected to the connector brackets 17^a by suitable bolts 98. An elongated slot 99 is provided in each of the connector brackets 17^a for receiving the brackets 97 whereby they may be moved to selected positions.

Each of the connector brackets is provided with a downwardly opening recess 101 adjacent the forward end thereof for receiving a top roll 14^a. The rear portion of the connector bracket 17^a extends transversely of the shaft of a top roll 16^a.

The top rolls 14^a and 16^a cooperate with bottom line rolls 12^a and 13^a in a manner well understood in the art. Passing around the top rolls 16^a and a top nose bar 102 is a top apron 91^a. In like manner, passing around the bottom rolls 13^a and a lower nose bar 103 is a bottom apron 92^a. The nose bars 102 and 103 are supported by a cradle assembly indicated generally at 104 whereby the nose bars 102 and 103 are adapted for free movement in a vertical plane toward and away from the top rolls 13^a and 16^a. The top nose bar 102 is of a substantial width, as clearly shown in FIGS. 5 and 6 to prevent or hinder apron separation. The nose bar 102 is held in spaced relation to the shaft of the top rolls 16^a by suitable brackets 106 having open slots 107 in the ends thereof for engaging the shafts of the associated top rolls. Preferably, bearing inserts 108 are inserted in the openings 107. Such bearing inserts may be formed of any suitable material, such as plastic or the like.

From the foregoing, it will be seen that I have devised an improved top roll assembly. By providing a top roll assembly wherein the downward pressure exerted by the pressure unit is in a generally downwardly and rearwardly direction, the tension on the bottom aprons may be reduced and accurately controlled whereby the top roll assembly is perfectly free to adjust its position according to the diameters of the bottom line aprons. Also, by providing an over arm assembly which may be readily assembled and disassembled by the release of a single nut, the over all time for installation and maintenance of my apparatus is greatly reduced. Furthermore, by providing a pressure unit wherein pressure is applied to a subjacent connector bracket by a roller and groove arrangement, the forward thrust may be increased or decreased and at the same time the pressure unit is held against lateral shifting.

While I have shown my invention in several forms, it will be obvious to those skilled in the art that it is not so limited, but is susceptible of various other changes and modifications without departing from the spirit thereof, and I desire, therefore, that only such limitations shall be placed thereupon as are specifically set forth in the appended claims.

What I claim is:

1. In a top roll assembly for fiber attenuating apparatus including a supporting roll stand, top rolls and bottom line rolls
  - (a) an over arm having a housing of generally inverted U-shape as viewed in cross section,
  - (b) means pivotally supporting said over arm adjacent the rear of said roll stand whereby said over arm extends forwardly thereof,
  - (c) adjustable means to lock said over arm against upward movement relative to said roll stand,
  - (d) an inwardly projecting adjustable bracket carried by the inner surface of said over arm,
  - (e) means to hold said bracket in selected positions relative to said over arm,
  - (f) a first pressure lever pivotally connected adjacent one end to said bracket,
  - (g) a spring member interposed between the other end of said first pressure lever and said bracket to exert

force in a direction to move said other end away from said bracket,

(h) and a second pressure lever pivotally connected intermediate its ends to said first pressure lever between said spring member and the point said first pressure lever is connected to said bracket and disposed to exert downward force on the top rolls.

2. In a top roll assembly for fiber attenuating apparatus as defined in claim 1 in which adjustable means is provided for adjusting the level of said first pressure lever, said adjustable means being accessible at a point outwardly of said over arm, there being an opening through said over arm providing visible means of determining the position of said first pressure lever.

15 3. In an over arm as defined in claim 1 in which a yoke member connects the second pressure lever to said first pressure lever and the width of said second pressure lever is substantially equal the width of said U-shaped housing of the over arm to thereby maintain said second pressure lever in parallel alignment with said over arm.

4. In an over arm as defined in claim 1 in which a forward portion of said second pressure lever holds and aligns one of said top rolls and the rear portion of said second pressure lever carries a roller which engages at 25 selected positions an elongated connector bracket that extends transversely of a pair of said top rolls.

5. In an over arm as defined in claim 4 in which the roller is disc shaped and an elongated recess is provided in the top of said connector bracket in position to receive 30 said roller and of a width substantially equal the width of said roller whereby said connector bracket is held against lateral shifting.

6. In an over arm as defined in claim 4 in which the roller is connected to said second pressure lever by a pin, there being a plurality of spaced openings through said second pressure lever for receiving said pin whereby said roller is held at selected positions.

7. In an over arm as defined in claim 5 in which the base of said elongated recess is inclined in a direction to retard forward movement of said connector bracket.

8. In a top roll assembly for fiber attenuating apparatus including supporting roll stands, top rolls and bottom line rolls,

- (a) a bracket extending transversely of a pair of said top rolls in position to apply downward pressure thereto and adapted to hold said top rolls in transverse alignment with said bracket,
- (b) a double boss top nose bar carried by said bracket in parallel alignment with said top rolls,
- (c) top aprons encircling said top nose bar and the adjacent to roll carried by said bracket,
- (d) a double boss bottom nose bar carried by said bracket in parallel alignment with said top rolls and said top nose bar,
- (e) bottom aprons encircling said bottom nose bar and an adjacent bottom line roll in position to contact the under surfaces of said top aprons,
- (f) there being a longitudinally extending recess in the upper surface of said bracket intermediate said pair of rolls with the base of said recess being inclined longitudinally at an angle for a portion of the downward pressure exerted on said bracket to control forward thrust of said bracket and tension on the bottom aprons,
- (g) a pressure roller mounted above said bracket with the lower surface thereof in engagement with the base of said recess,
- (h) said roller being of a size to limit lateral movement of said bracket and permit free forward and rearward movement of said bracket relative to said roller whereby forward movement of said bracket is limited solely by said bottom aprons,
- (i) and pressure means operatively connected to said roller to apply downward pressure thereto and thereby impart downward pressure on said bracket.

9. A top roll assembly for fiber attenuating apparatus as defined in claim 8 in which vertically extending apron guide pins are carried by said top and bottom nose bars.

10. A top roll assembly for fiber attenuating apparatus as defined in claim 8 in which the base of the recess in said bracket is sloped downwardly and forwardly for a portion of the downward pressure exerted on said bracket to restrain forward thrust of said bracket thereby reducing and controlling tension on the bottom aprons.

11. A top roll assembly for fiber attenuating apparatus as defined in claim 8 in which vertically spaced, forwardly opening slots are provided in the forward portion of said

bracket for receiving the top nose bar and the bottom nose bar, and means is carried by said bracket for retaining said nose bars in fixed positions within said slots.
